(57) **CLAIM**

The ornamental design for an espresso coffee machine as shown and described.

DESCRIPTION

1. Espresso coffee machine

1.1 : Perspective

1.2 : Front

1.3 : Back

1.4 : Left

1.5 : Right

1.6 : Top

1.7 : Bottom

The broken lines illustrate portions of the espresso coffee machine excluded from protection and that form no part of the claimed design. The surface immediately adjacent to and outside of the broken line shown on the bottom of the espresso coffee machine in reproduction 1.7 forms no part of the claimed design.
